(**) Term: **14 Years**

(57) **CLAIM**

(21) Appl. No.: **29/156,346**

The ornamental design for an electrical interconnect having an integral helically shaped resilient portion, as shown and described.

(22) Filed: **Feb. 28, 2002**

DESCRIPTION

(51) LOC (7) Cl. **13-03**
(52) U.S. Cl. **D13/133**
(58) Field of Search ..... D13/133, 154; 439/445, 448, 449; 174/74 A, 135, 138 R

(56) **References Cited**

This patent application is related to a patent application of the same applicant entitled “Electrical Interconnect having an Integral Resilient Portion” simultaneously filed and copending with this application.

FIG. 1 is a top front perspective view of an electrical interconnect having an integral helically shaped resilient portion showing my new design.

FIG. 2 is a side elevational view thereof.

FIG. 3 is a top elevational view thereof; and,

FIG. 4 is a bottom elevational view thereof.
